CLAIM

The ornamental design for a trading card display system, as shown and described.

DESCRIPTION

FIG. 1 is a front isometric view of my trading card display system;

FIG. 2 is a side isometric view of my system;

FIG. 3 is a side elevational view of my system, with the opposite side being a mirror image thereof; and,
FIG. 4 is a bottom plan view of my system.

1 Claim, 2 Drawing Sheets
